UNITED STATES PATENT OFFICE.

LOCKWOOD B. ELLIS, OF DETROIT, MICHIGAN, ASSIGNOR TO GENERAL MOTORS CORPORATION, OF DETROIT, MICHIGAN, A CORPORATION OF DELAWARE.

INTERNAL-COMBUSTION ENGINE.

Application filed August 6, 1924. Serial No. 730,458.

This invention relates to engines, and is illustrated as embodied in the V-type eight cylinder engine of a Cadillac automobile. Among the objects of the invention are the efficient lubrication of the valve mechanism, and the elimination from the oil of fuel and water escaping past the pistons.

Having these objects in view, the oil and fuel and water are collected, preferably under some pressure, in spaces of novel form in the pistons, and are discharged through openings in the cylinder walls. In considering the lubrication of the valve tappets or other mechanism, I consider it highly desirable that these openings have fittings formed to discharge the oil as a spray or mist into an inclosure or chamber for the tappets. Regarding the invention as directed to freeing the oil of fuel and water, the mixture of fluids is collected in a pocket which is subject to the heat of the cylinders, the mixture also preferably being agitated by arranging the fittings to discharge under the surface of the fluids in the pocket. Thus the fuel and water are in effect distilled off and escape as vapors into the atmosphere, for example through the breather tube. The oil is returned to the crankcase for further use.

The above and other objects of the invention, together with various novel and desirable particular constructions, will be apparent from the following description of illustrative embodiments shown in the accompanying drawings, in which:

Figure 1 is a view, partly in end elevation and partly in vertical section through one of the cylinders, of the engine;

Figure 2 is a view, on the line 2—2 of Figure 1, showing in side elevation part of the bottom section of the cylinder block;

Figure 3 is a section on the line 3—3 of Figure 1, through the cylinder block at right angles to the axes of the cylinders, but with the valves and their casing removed;

Figure 4 is a vertical section, on the line 4—4 of Figure 2, through the bottom section of the cylinder block, on one side only;

Figure 5 is a vertical section on the line 5—5 of Figure 3, through the lower part of a passage forming a continuation or part of the breather tube;

Figure 6 is a view corresponding to part

of Figure 1, but showing a modified arrangement; and

Figure 7 is a section through one of the above-described fittings.

Figures 3, and 7 are on a larger scale than the other figures.

The invention is shown as embodied in an engine having a crankcase 10 with two blocks 12 of four cylinders 14 each, arranged in V relation on the crankcase. In each block 12, the cylinders 14 are in two pairs, with a passage 16 between the pairs, a breather tube 18 forming a continuation of the passage 16 as is usual in the Cadillac engine. The breather tube is held in the usual manner, by a bolt or bolts 20, clamped against the side of the passage 16. Valves 22 have tappets 24, or equivalent operating mechanism, on the inside of the V, and a piston 26 with its connecting rod 28 is arranged in each cylinder. Adjacent pairs of cylinders 14 are connected by webs 30, and the wall of passage 16 is connected to the two middle cylinders 14 by webs 32. The above-described parts may be of any desired construction.

In the arrangement shown in Figures 1—5, each piston 26, which has the usual grooves for piston rings 34, has a pair of side grooves 36 leading from the lowest piston ring groove, and communicating with a hollow piston pin 38 connecting the piston to its connecting rod 28. These grooves intersect a circumferential groove 40 which leads to a discharge groove 42 parallel to and between the grooves 36.

Each time the piston approaches its lowermost position, discharge groove 42 registers with an opening in the cylinder wall, in which is threaded a fitting 44. Each fitting has a central passage 46 leading from its cylinder, and an intersecting cross passage 48 discharging into an inclosure formed by the cylinder block and a cover plate 50, and in which are arranged the tappet rods 24. Fuel and water, either condensed or as vapors, escaping past the piston rings 34, together with oil from the cylinder walls, collect in the hollow piston pin 38 and the various described grooves in the piston skirt, under more or less pressure from the compression or explosion stroke, and when groove 42 registers with fitting 44 they are sprayed into the valve tappet inclosure, thus

producing therein a slowly-settling mist or vapor of oil which efficiently lubricates the tappets.

Fittings 44 for each pair of cylinders discharge into a pocket formed by a ledge 52 on the cylinder casting, at such a height that the mixture of fluids is subject to the heat of the cylinder walls, which in effect distills off the water and fuel as vapors, leaving the oil to overflow into a lower pocket formed by a flange or ledge 54 on the bottom of the casting, and which is common to all four of the cylinders and to the passage 16. As shown in Figure 5, surplus oil drains back into the crankcase through an opening 56 in the wall of passage 16, which opening may also serve for the escape of water and fuel vapors into the atmosphere through the breather tube 18. In order to facilitate the above-described action, fittings 44 discharge into the pocket formed by ledge 52 below the level of the fluids collected therein, to agitate them by spraying the incoming fluids through them (see Figure 4).

If desired, louvered openings 60 may be formed in plate 50, to permit the water and fuel vapors to discharge directly into the atmosphere. When openings 60 are provided there is more or less communication of vapors from the crankcase through the passage 56 into the tappet enclosure, and from the latter said vapors may escape through said openings.

In the modification shown in Figure 6, there is no ledge 52, the mixed oil and fuel and water collecting directly on flange 54. In this modification, also, the circumferential groove 240 in piston 26 is directly below the grooves for the piston rings, and communicates with a downwardly-extending groove 242, which registers once each stroke with fitting 44.

While particular embodiments of the invention have been described in detail, it is not my intention to limit its scope to those embodiments, or otherwise than by the terms of the appended claims.

I claim:

1. An internal combustion engine comprising a cylinder, a valve therefor, a tappet for said valve, an enclosure for said tappet, means for admitting lubricating oil to said enclosure, and means for retaining said oil within said enclosure while subjecting it to heat sufficient for distilling vapors of contaminating liquid therefrom.

2. An internal combustion engine comprising, in combination, a cylinder having an opening in its side, a piston having a groove communicating periodically with the opening and a space communicating with the groove and adapted to receive oil and condensed fuel and water, valves having tappets, an enclosure for the tappets in communication with the opening in the side of the

cylinder, and means in the inclosure to hold the oil and water and fuel subject to the heat of the cylinder to distill off the fuel and water.

3. An internal combustion engine comprising, in combination, a crankcase, a cylinder having an opening in its side and a ledge forming a pocket below the opening, the pocket being subject to the heat of the cylinder when the engine is running, a piston in the cylinder having a space receiving oil and fuel and water and which registers periodically with the opening to discharge the oil and fuel and water into the pocket, and means to discharge into the atmosphere the fuel and water distilled off from the oil as vapors and to return to the crankcase the liquid oil.

4. An internal combustion engine comprising, in combination, a crankcase, a cylinder having an opening in its side and a ledge forming a pocket below the opening, the pocket being subject to the heat of the cylinder when the engine is running, a fitting in the opening discharging below the level of liquid in the pocket to agitate the liquid, a piston in the cylinder having a space receiving oil and fuel and water and which registers periodically with the fitting to discharge the oil and fuel and water into the pocket, and means to discharge into the atmosphere the fuel and water distilled off from the oil as vapors and to return to the crankcase the liquid oil.

5. An internal combustion engine as defined by claim 3, in combination with valves having tappets, and an inclosure for the tappets containing said ledge and pocket.

6. An internal combustion engine comprising, in combination, a crankcase, a cylinder having an opening in its side and a ledge forming a pocket below the opening, the pocket being subject to the heat of the cylinder when the engine is running, a piston in the cylinder having a space receiving oil and fuel and water and which registers periodically with the opening to discharge the oil and fuel and water into the pocket, an inclosure for said pocket, and a breather tube opening from the crankcase into the atmosphere and communicating with the inclosure to receive liquid oil therefrom and to return it to the crankcase, and to receive fuel and water as vapors and discharge them into the atmosphere.

7. A piston having a hollow piston pin, piston ring grooves, side grooves from the piston ring grooves communicating with the hollow piston pin, a circumferential groove communicating with the side grooves, and a discharge groove leading from the circumferential groove along the side of the piston between and parallel to the side grooves.

8. An engine comprising, in combination, a plurality of cylinders arranged in two

- groups, a crankcase for the cylinders, a breather tube between the groups of cylinders and which communicates at its lower end with the crankcase and at its upper end with the atmosphere, valves having tappets along the sides of the cylinders, a plate forming with the cylinders an inclosure for the tappets, a fitting in the wall of each cylinder opening into the inclosure, a discharge opening from the inclosure to the breather tube, and pistons in the cylinders constructed and arranged to collect oil and fuel and water and discharge them into the enclosure through said fittings.
- 15 9. An engine comprising, in combustion, a cylinder having an opening in its side, a piston having a fluid-collecting space registering periodically with the opening, a fitting in the opening having a central passage communicating with the inside of the cylinder and having an intersecting cross passage discharging at opposite sides of the fitting, and valve mechanism arranged to be lubricated by oil sprayed from said space through the fitting.
- 20 10. An engine comprising, in combination, a block of cylinders, a valve tappet chamber at one side of the block including a cover having louvered openings discharging into the atmosphere, and means for collecting surplus oil and water and fuel vapors in the cylinders and discharging them into the chamber.
- 25 11. An internal combustion engine comprising a cylinder, a valve therefor, valve operating means, an enclosure for said operating means, means for supplying lubricant to said enclosure, and means within said enclosure for retaining said lubricating oil and subjecting it to heat sufficient for distilling vapors of contaminating liquids therefrom.
- 30 12. An internal combustion engine comprising in combination with the crankcase, piston valve, valve operating mechanism and the enclosure thereof, means forming a passage through which vapors generated
- 35 by the engine may escape into said enclosure without passing into said crankcase, and means forming a second opening 50 through which they may escape therefrom.
- 40 13. An internal combustion engine comprising a cylinder and piston, said piston being formed to collect lubricating oil under pressure, a valve for said cylinder, valve operating means and an enclosure therefor, said cylinder having an opening through which said collected lubricant is intermittently discharged into said enclosure, means within said enclosure for subjecting said lubricating oil to heat sufficient for distilling vapors of contaminating liquids from said oil, and openings from said enclosure through which said vapors and said oil respectively escape.
- 45 14. An internal combustion engine comprising a crankcase, a cylinder, a piston therefor, a valve, valve operating mechanism and an enclosure therefor, the wall of said cylinder having an opening arranged 70 to be uncovered during the movement of the piston and leading to said enclosure for permitting vapors from the crankcase to escape into said enclosure for lubricating said valve operating mechanism and valve, there 75 being a small second opening leading from said enclosure to permit said vapors to escape.
- 50 15. An internal combustion engine comprising a cylinder, a piston therefor, a valve, 80 a tappet and a tappet enclosure, said piston and cylinder together comprising means for collecting lubricant and vapors and for discharging them into said tappet enclosure, means on the wall of said cylinder within 85 said enclosure forming a pocket in which said oil is collected, said pocket being so positioned as to be subjected to a temperature such that vapor is distilled from the oil therein, there being an opening from said 90 enclosure through which said oil is thereafter returned to the crankcase by gravity.
- In testimony whereof I affix my signature.
